UNITED STATES PATENT OFFICE.

FRANZ LOUIS MÄDLER, OF BERLIN-CHARLOTTENBURG, GERMANY, ASSIGNOR TO
MAEDLER ENGINE CORPORATION, A CORPORATION OF MARYLAND.

VALVE-GEAR CONNECTION IN INTERNAL-COMBUSTION ENGINES.

Application filed April 6, 1921. Serial No. 459,191.

(GRANTED UNDER THE PROVISIONS OF THE ACT OF MARCH 3, 1921, 41 STAT. L., 1313.)

To all whom it may concern:

Be it known that I, FRANZ LOUIS MÄDLER, a citizen of the German Empire, residing at Berlin-Charlottenburg, Germany, have invented certain new and useful Improvements in Valve-Gear Connections in Internal-Combustion Engines (for which patent applications have been filed on the following dates in the following countries foreign to the 10 United States, Germany, April 8, 1918; Austria, June 9, 1920; Hungary, July 9, 1920; Czechoslovakia, June 17, 1920; Poland, June 28, 1920; England, July 3, 1920; Canada, July 10, 1920; Switzerland, June 12, 15 1920; France, July 10, 1920), of which the following is a specification.

My invention refers to internal combustion engines and more especially to the arrangement of the valve gear connected with such 20 engines. Its particular object is to relieve the cylinders of such engines almost entirely of all detrimental additional stresses such as might be caused by the operation of the valve gear.

25 In the design of airplane engines it is essential, in view of the light construction used, particularly in cylinders and water jackets, to relieve the cylinders of detrimental strains that are caused by the operation 30 of overhead valves.

In my invention, the cylinder is subjected to only such stresses as may be caused by the compression of the valve spring, and not to the sudden acute pressures caused by the 35 acceleration of the valve-operating mechanism. I accomplish this object either by rigidly supporting the fulcrum of the valve-operating lever from the crank-case, or by sustaining the thrust on the fulcrum of the 40 valve-operating lever by a non-rigid tension member.

In the drawings affixed to this specification and forming part thereof, two modifications of an internal combustion engine embodying my invention are illustrated by way of example. In said drawings,

45 Figs. 1 and 2 are respectively an elevation partly in section, and a plan, of the one modification, while

50 Fig. 3 is a vertical section of the other modification.

Referring to Figs. 1 and 2 of the draw-

ings, the stay bolts *a* of the cylinder *y* which extend right through from top to bottom, are extended upwardly to receive tubular supports *b* of light metal such as aluminum which are preferably united in pairs for instance by suitable webs and are slipped over the said bolts.

These tubular supports *b* carry cross-beams *c* constructed in two parts to accommodate the axles *d* for the rocking levers *g* which operate the valves, said axles *d* being firmly held between the component parts of the said beams. The valve-levers *g* are 60 operated by the push rods *h*. The clamping of the axles between the cross-beams *c* is effected by means of the nuts *e* which also fix the axles *d* upon the supports *b* and thus upon the crank-case *f*, so that an absolutely 65 rigid connection with the crank-case is established and the cylinders themselves are entirely relieved from the stresses resulting from the actuation of the valves.

In the operation of Figs. 1 and 2 it will 70 be seen that the cam-shafts 5 actuate push rods *h* and these operate the rocking levers *g*, which in turn actuate valves *i*. The rocking levers *g*, being supported on axles *d*, which are rigidly held by stay bolts *a* on the top of supports *b*, are rigidly connected to and supported upon the crank case *f* independently of the cylinders. Consequently, 75 whatever strains occur in the operation of the valve-operating mechanism are taken up 80 by the axles *d*, which are rigidly connected to and supported by the crank case.

In the modification illustrated in Fig. 3, the rocking lever *g* operating the valve *i* is 85 permanently linked at 10 to the end of the valve stem 2, and is operatively attached to the cam-operated rod *h* at point 3. The valve *i* is normally held closed by a strong 90 spring 4.

It will be clear that, when the rod *h* 95 is moved upwards by the action of the cam-shaft 5 to open valve *i* against the pressure of spring 4, the link *k* is subjected to an upward pull as the lever *g* is rocked about the point *l* where the link is attached. Since, therefore, the link *k* is subjected only to a 100 pull or tension, it is obvious that it need not be rigid but can be made out of a light rod, steel wire, metallic strip, or the like, having

sufficient tensile strength to withstand a heavy pull.

On account of an official requirement of division, I make no claims herein to the construction shown in Fig. 3, for which I am about to file a divisional application.

With this arrangement the cylinder is subjected also only to such stresses as are caused by the varying pressures of the 10 valve spring resulting from the actuation of the valve.

It will be understood that in so far as the valve *i* and its connection with the valve-lever *g* are concerned, the illustration in 15 Fig. 1 is of a diagrammatic nature, the arrangement in practice including a spring for returning the valve to its closed position, said spring being located and arranged as in Fig. 3 or in any other equivalent manner; 20 obviously the valve *i* in Fig. 1 operates to control a port of the cylinder in the same way as illustrated in Fig. 3.

I claim:

1. In light-weight internal combustion engines, the combination of a crank case, a cylinder having a port, a valve controlling said port, a valve lever for operating said valve, an axial carrying said valve lever, tubular supports extending upwardly from said 25 crank case and carrying said axial, and stay bolts extending from said crank case through said supports for connecting the lat-

ter and said axle with each other and with said crank case independently of said cylinder, whereby the latter is relieved of 35 stresses incident to the actuation of said valve.

2. In light-weight internal combustion engines, the combination of a crank case, a cylinder having a port, a valve controlling 40 said port, a valve lever for operating said valve, an axial carrying said valve lever, tubular supports extending upwardly from said crank case, two-part cross-bars carried 45 by said supports and mounting said axle thereon, and stay bolts extending from said crank case through said supports for clamping said cross-bars upon said axles and for fixing said supports upon said crank case independently of said cylinder, whereby the 50 latter is relieved of stresses incident to the actuation of said valve.

3. In an internal combustion engine, a support for valve-operating mechanism comprising a plurality of tubular members 55 resting on the crank case of the engine, and bolts passing through said tubular members and holding said valve-operating mechanism firmly on top of said tubular members independently of the engine cylinder, whereby 60 the cylinder is relieved of all stresses incident to the actuation of said mechanism.

In testimony whereof I affix my signature.

FRANZ LOUIS MÄDLER.
